UNITED STATES PATENT OFFICE.

JOHN WILLIAM FEENY AND ROE REILLY, OF ELMIRA, NEW YORK.

DESIGN FOR A COAL-SCUTTLE.

SPECIFICATION forming part of Design No. 24,947, dated December 3, 1895.

Application filed November 2, 1895. Serial No. 567,763. Term of patent 14 years.

To all whom it may concern:

Be it known that we, JOHN WILLIAM FEENY and ROE REILLY, of Elmira, in the county of Chemung and State of New York, have invented and produced a new and original Design for a Coal-Scuttle, of which the following is a full, clear, and exact description.

Reference is to be had to the accompanying drawings, forming a part of this specification.

10 In the said drawings, Figure 1 is a perspective view of a coal-scuttle embodying our new design, and Fig. 2 is an inverted plan view.

The leading feature of the design consists in the coal-scuttle having its back flat and 15 rising above the body of the scuttle, as shown.

Other features of our design reside in the said flat back having its projecting upper end *a* flaring at an angle to the lower part of said back, in the bottom rim *b* presenting the appearance of a horseshoe as viewed from below, and in the arched handle *c* disposed transversely within said bottom rim.

We claim—

The design for a coal scuttle herein shown and described.

JOHN WILLIAM FEENY.
ROE REILLY.
